BELT-BUCKLE ASSEMBLY

Jack Lesser, Wynco, and Leon H. Halber, Philadelphia, Pa., assignors to Atlas Novelty Company, Inc., Philadelphia, Pa., a corporation of Pennsylvania
Filed Feb. 28, 1962, Ser. No. 176,374
6 Claims. (Cl. 40—21)

This invention relates to a belt and belt-buckle assembly, and it particularly relates to an assembly of the aforesaid type wherein the buckle is also a receptacle for identification data. This is a continuation-in-part of co-pending application Serial No. 127,285, filed July 27, 1961, and is an improvement over the belt and buckle assembly called for in my co-pending application Serial No. 127,285, filed July 27, 1961, now Patent No. 3,043,037 issued July 10, 1962.

In the aforementioned co-pending application, there was disclosed a belt-buckle of the hook type for insertion of the hook into a selected hole in a belt. This buckle had a receptacle portion for releasably holding a folded strip of paper or the like containing identification data. However, although the buckle disclosed in said co-pending application is, in many ways, most adequate for its purposes, it has certain disadvantages inherent therein both as regards its data-holding and locking means and the cost of manufacture.

It is an object of the present invention to overcome the disadvantages and defects of the prior art, as set forth in said co-pending application, and at the same time to improve upon the device disclosed in said co-pending application itself.

Another object of the present invention is to obtain the utmost in safety and reliability both in the belt-holding and data-holding aspects of the buckle while keeping the device very simple in construction and very easy to manipulate.

Other objects and many of the attendant advantages of this invention will be readily appreciated as the same becomes better understood by reference to the following detailed description when considered in connection with the accompanying drawings wherein:

FIG. 1 is a fragmentary side elevational view of a belt and belt-buckle assembly embodying the present invention.

FIG. 2 is a partly sectional and partly elevational view with the section taken on line 2—2 of FIG. 1.

FIG. 3 is a perspective view of the buckle of FIGS. 1 and 2, with the receptacle portion of the buckle being shown in the open position and the data sheet being shown outside the receptacle.

Referring now in greater detail to the various figures of the drawing wherein similar reference characters refer to similar parts, there is shown a belt and belt-buckle assembly, generally designated 10, comprising a belt 12 and a buckle 14.

The belt 12 is of the ordinary type wherein one end is looped at 16 through the opening 17 of an offset hollow bracket 18 at one end of the buckle 14, the loop on the belt being secured to the bracket by stitching, stapling or the like 20. The other end of the belt 12 is provided with a series of holes 22 for selectively receiving a hook 24 at the opposite end of the buckle from where the bracket 18 is situated. It should be noted that the hook 24 extends rearwardly of the buckle 14 to a plane which is common with the free end portion of the hollow bracket 18. By means of this construction, when the hook 24 is positioned through a hole 22 to secure the belt around the waist of the wearer, the end of the hook 24 and end of the bracket 18 act to space the buckle a sufficient distance away from the wearer's body to permit easy en-

2

trance of the free end of the belt behind the buckle (as indicated in FIG. 2). Furthermore, since a portion of the opening 17 of the bracket 18 is offset from the end of the bracket to which the loop 16 is attached and since this offset portion of the opening is in the plane of the free end of the belt (as shown in FIG. 2), if the belt is to be tightened to where a considerable portion of the free end of the belt hangs loose, this loose end may be conveniently passed through the offset portion of the opening 17 whereby the bracket 18 acts as a retainer for the loose end of the belt.

The buckle 14 itself comprises a generally rectangular housing 26 made of metal or the like and defined by upper and lower walls 28 and 30 and rear wall 32. The upper and lower walls 28 and 30 are each provided with a generally oval-shaped aperture, as at 34 and 36 respectively, these apertures being arranged adjacent the left end of these walls (as viewed in the drawing) and in vertical alignment with each other.

20 The apertures 34 and 36 serve as journals to pivotally support upper and lower vertical hinge-pin extensions 38 of a flange 40 integral with one edge of a cover plate 42. The opposite edge of the cover plate 42 is also provided with a flange 44 similar to and parallel with the flange 40. The flange 44 is provided with a small recess 46 in the central portion of its outer surface and this recess 46 is adapted to receive and frictionally engage with a lug 48 on the inner surface of a latch plate 50 integral with and perpendicular to the remote edge of the 25 rear wall 32 of the housing, whereby the cover plate 42 is releasably locked in the closed position. Integral with the lower end of the free edge of the flange 44 is a perpendicularly extending handle or finger-grip 52 having a 30 weight-decreasing aperture 54. The handle 52 has a 35 slightly offset free edge 56 which permits it to be more easily grasped when the cover plate 42 is in the closed position (as in FIG. 1).

In order to securely hold the data sheet 58 in position when the cover plate is open, there is provided a spring 40 finger 60 struck out from the rear wall 32 of the housing 26. This finger is positioned adjacent the left end of the housing (as viewed in the drawing) so that it provides a minimum of interference with insertion of the data sheet and simultaneously permits easy engagement of an 45 edge of the data sheet therewith.

It should be noted that the above construction permits simple and inexpensive fabrication because no end walls are necessary on the housing, the flange 40 and finger 50 supplying these functions when the cover plate is open. 50 In this respect, the flange 50 permits simple hinging of the cover plate to the housing since this flange acts as a retaining wall for the housing both in the open and closed 55 positions of the cover plate and yet does not interfere with the swinging of the cover plate from one position to another. It should also be noted that the positioning of the handle 52 in an offset relation with respect to the latch finger 50 eliminates the necessity of making the catch finger movable to permit disengagement and also provides a leverage between the catch and the handle. 60 This leverage permits the catch to be made quite strong while yet being easily openable.

Obviously many modifications and variations of the present invention are possible in the light of the above teachings. It is, therefore, to be understood that within 65 the scope of the appended claims, the invention may be practiced otherwise than as specifically described.

The invention claimed is:

1. A belt-buckle assembly comprising a housing, a cover plate hinged to said housing, a bracket at one end 70 of said housing, and a hook at the opposite end, said bracket having an opening therein, the portion of the bracket defining said opening having an offset stepped

configuration whereby it extends from the plane of said housing to an offset plane rearwardly thereof, said hook also extending from said housing to said offset plane, said housing being defined by a rear wall and upper and lower walls, said cover plate being hingedly connected to said upper and lower walls at one edge of said rear wall for pivotal movement into and out of closed position against the open face of said housing and having an offset flange which is pivotally arranged between said upper and lower walls to define a pivotally movable side wall of said housing, the opposite edge of said rear wall having a perpendicularly extending latch plate thereon projecting forwardly of said rear wall and provided with a latch lug, a second offset flange on said cover plate in spaced relation to said first-mentioned offset flange, a recess in said second offset flange of said cover plate adapted to be frictionally engaged by said latch lug when said cover plate is in closed position on said housing, and a clamping finger within said housing adjacent that edge thereof to which said cover plate is hingedly connected.

2. The assembly of claim 1 wherein a finger-grip handle is provided on said second offset flange of said cover plate in spaced offset relation to said recess.

3. A belt-buckle assembly comprising a generally flat buckle plate having a front face, a rear face, a first edge and a second edge opposite each other and a third and a fourth edge opposite each other and extending between said first and second edges, each of said third and fourth edges having a lateral flange extending along the length thereof and projecting forwardly of the front face of said buckle plate, an offset bracket at said first edge, said bracket having an aperture therein for receiving and attaching of a belt thereto, said bracket and said aperture being stepped in a direction rearwardly of said buckle plate, a hook at the second edge of said buckle plate for selective insertion in holes of a belt, said hook extending

5 rearwardly of said buckle plate with the free end of said hook in a common plane with the rear end of said bracket, a clamping finger on the front face of said buckle plate for releasably holding a data sheet thereon, a cover plate hingedly positioned on a hinge axis between said lateral flanges on the third and fourth edges of the buckle plate and adjacent said second edge, said cover plate being hingedly movable from a closed position parallel to and spaced from the front face of said buckle plate to an open position in substantially the plane of said buckle plate, a closure flange extending laterally from said cover plate at the hinge axis thereof, said closure flange being constructed and arranged to form a forwardly-extending end wall for said buckle plate in both the closed and open positions of said cover plate, and a latch means for releasably holding said cover plate in its closed position.

rearwardly of said buckle plate with the free end of said hook in a common plane with the rear end of said bracket, a clamping finger on the front face of said buckle plate for releasably holding a data sheet thereon, a cover plate hingedly positioned on a hinge axis between said lateral flanges on the third and fourth edges of the buckle plate and adjacent said second edge, said cover plate being hingedly movable from a closed position parallel to and spaced from the front face of said buckle plate to an open position in substantially the plane of said buckle plate, a closure flange extending laterally from said cover plate at the hinge axis thereof, said closure flange being constructed and arranged to form a forwardly-extending end wall for said buckle plate in both the closed and open positions of said cover plate, and a latch means for releasably holding said cover plate in its closed position.

4. The assembly of claim 3 wherein a finger-grip handle is provided on said cover plate in a spaced offset position relative to said latch means when said cover plate is in closed position.

5. The assembly of claim 3 wherein said latch means comprises a lug connected to said first edge and a recess on said cover plate adapted to receive and be frictionally engaged by said lug when said cover plate is in closed position.

6. The assembly of claim 3 wherein said clamping finger comprises a spring finger positioned on the front face of said buckle plate adjacent one end thereof and in an opposite position relative to said latch means.
